UNITED STATES PATENT OFFICE.

JESSE SUMMERS AND HERBERT E. SUMMERS, OF INDIANAPOLIS, INDIANA,
ASSIGNORS TO THE INDIANAPOLIS WATCHMAN CLOCK COMPANY, OF
INDIANAPOLIS, INDIANA, A CORPORATION OF INDIANA.

WATCHMAN'S TIME-RECORDER.

SPECIFICATION forming part of Letters Patent No. 767,453, dated August 16, 1904.

Application filed March 20, 1903. Serial No. 148,710. (No model.)

To all whom it may concern:

Be it known that we, JESSE SUMMERS and HERBERT E. SUMMERS, citizens of the United States, residing at Indianapolis, in the county 5 of Marion and State of Indiana, have invented certain new and useful Improvements in Watchmen's Clocks, of which the following is a specification.

The objects of our invention are to provide 10 in a watchman's time-recorder or clock means by which the several station numbers, letters, or indicators may be printed upon that face of the dial which is visible when in operative position and by which the movement of the 15 dial cannot be affected; means by which, if an indication is not sent in from particular stations at predetermined times, an independent alarm will be sounded or given; means by which the apparatus may not be unlocked during 20 certain portions of the day, but by which the apparatus may be unlocked during other predetermined portions of the day, and such improvements in details of construction as are hereinafter pointed out.

25 The accompanying drawings illustrate our invention.

Figure 1 is a front elevation of our apparatus with the usual paper dial and the door removed. Fig. 2 is a similar view with a suitable 30 paper dial in position. Fig. 3 is a diagram of the wiring of our apparatus in connection with six stations. Fig. 4 is a sectional detail of the printing mechanism. Fig. 5 is an elevation of the type-holding platen. Fig. 6 is a detail 35 of the electric lock. Fig. 7 is a detail of the means for operating the automatic alarm mechanism. Fig. 8 is a sectional detail of the dial-holding means.

Our apparatus consists of a suitable time-train 40 10, having the usual hour-hand arbor 11, which is revolved for convenience once in each twenty-four hours, to which is secured a head or disk 12, provided with a pair of pins 13, which are adapted to pass through the 45 suitable dial 14 and enter corresponding holes formed in a removable disk 15, which may be slipped upon or removed from the arbor 11

in the usual well-known manner. Rotated by the time-train is a time-disk 16, having formed therein a slot 17, which is of such length that 50 it will require, say, thirteen hours to pass the coöoperating terminal 18. Disk 16 also has formed therein a slot 19—say eleven hours long—which is adapted to coöperate with terminal 20. Driven by the time-train, so as to 55 make, preferably, one revolution an hour, is a disk or head 21, which has formed therein at desired intervals radial slots 22, into any one of which may be slipped the inner end of a spring brush-terminal 23, which is adapted to 60 contact with stationary terminals 24 and 25.

Lying in front of the dial 14 is a type-holding arm or platen 26, which projects radially over the face of the dial and is provided in its inner face with a plurality of type-holding 65 holes 27, within which may be placed type 28 of any suitable form. For convenience we find that type such as those used in type-writing machines are available.

Leading from a suitable storage-drum 29 is 70 an inked ribbon 30, which passes between type 28 and the dial 14 and from thence outward and back over platen 26 to a suitable winding-drum 31, provided with a ratchet 32, adapted to be engaged by a spring-finger 33, carried 75 by the door 34 of a suitable inclosing cabinet 35, which is designed to contain the entire mechanism.

Located behind the dial 14 and opposite each type 28 is a hammer 36, each of which is carried by the vibrating arm 37 of an electric buzzer 38 of any usual or desirable type. The buzzers 38 may be supported by any suitable means; but in order to economize space and in order that the type 28 may be placed close 80 together, so that a comparatively small dial may be used for a comparatively large number of stations, we prefer to arrange the buzzers in the following manner: Supported in the casing 35 are posts 39, each carrying a 85 pair of arms 40, between which are supported curved bolts 41, upon which the buzzers may be strung, so that their arms 37 may converge toward the platen 26, the buzzers being held 90

in spaced position by sleeves 42, strung upon the bolts 41 between the buzzers in the usual well-known manner.

Located at a suitable point within casing 35 are two electromagnets 43 and 44, between which is pivoted an arm 45, which arm is adapted to contact at one end of its swing with a terminal 46. Arm 45, if arranged as shown in the drawings, will remain in either position by reason of its own weight; but its contact with the terminal 46 may be insured by arranging for a slight overlapping friction or by using a light spring-catch.

Located within the casing 35 at a point adjacent the door 34 is an electromagnet 47, the swinging armature 48 of which carries a lock-pin 49, which when the armature 48 is in the lowest position will pass through an eye 51, carried by door 34.

For the purpose of facilitating the setting of the dial 14 we provide a guide 52, which is supported within the casing 35 and carries a glass 53, having upon its face a gage-mark 54, before which any portion of the dial may be brought. For convenience we provide, besides the Roman numerals to indicate the hours, Arabic numerals 55, which are arranged adjacent the Roman numerals, but are six hours different therefrom, so that when the number 30 "6" is brought opposite the gage-mark on glass 53 the number "VI" will be in line with the type 28.

In wiring a six-station plant the stations 1, 2, 3, 4, 5, and 6 are placed at any desired points in the factory or place to be guarded and main-line wire 56 connected to one side of the push-button at each station, this line-wire 56 being connected by a wire 57 with a suitable battery 58. Leading from battery 58 and 40 from the time-train, so as to thus connect with the time-disk 16 and with the circuit-breaker 21, is a wire 59. Leading from the opposite side of the battery 58 is a wire 60, which leads to one side of coil 43, the other side of said coil being connected by wire 61 with terminal 25. Where disk 21 is provided with only two arms 23 and the disk 21 makes one revolution per hour, it is desirable that not all of the stations 1, 2, 3, 4, 5, and 6 be connected to coil 44 for 45 the reason that only part of the stations would probably be required to be operated at about the time when the arms 23 comes into contact with terminal 24. In Fig. 3 the two buzzers 38, which are connected to the terminals 1 and 2, are therefore connected by a wire 62 to one side of coil 44, while the opposite side of said coil is connected by a wire 63 with battery 58. The remaining buzzers are then connected directly by wire 64 with battery 58, the circuits 60 through these buzzers not passing through coil 44.

The coil 47 of the time-lock is connected on one side by wire 65 with a push-button 66, the opposite side of the said push-button being 65 connected by wire 67 to one side of the bat-

tery 58, while the opposite side of the coil 47 is connected by a wire 68 with the brush-terminal 20. Leading from brush-terminal 18 is a wire 69, which connects with one side of a second battery 70, the opposite side of said 70 battery being connected by wire 71 with an alarm 72, which is to be located at any desired point—as, for instance, at the home of the proprietor of the place to be guarded. The opposite side of said alarm is connected with 75 terminal 46, while armature 45 is connected to terminal 24.

In operation head 21 will be rotated, say, once an hour, while disk 16 will be rotated once in twenty-four hours. During the night 80 slot 19 will be opposite brush 20, and brush 18 will be in contact with disk 16, and during the day brush 20 will be in contact with disk 16, while the slot 17 of said disk will be opposite the end of brush 18. During 85 the night one of the arms 23 will come into contact with terminal 24 once each half-hour, and if armature 45 lies in contact with terminal 46 the alarm 72 will be sounded. If, however, the watchman has performed his 90 duty and has operated either one of the push-buttons 1 and 2, magnet 44 will be energized and armature 45 drawn away from terminal 46, so that at the time of contact of one of the arms 23 with terminal 24 the alarm-circuit 95 will continue broken. As head 21 continues to revolve the arm 23 which has been in contact with terminal 24 passes therefrom and contacts with terminal 25, thereby establishing a circuit through coil 43, so as to return armature 45 into contact with terminal 46. When the watchman has operated any one of the push-buttons at any one of the stations, the corresponding buzzer will vibrate its arm 37 and cause its hammer 36 to strike 100 dial 14 and carry the same against the corresponding type 28, so as to cause an imprint thereof upon the face of the dial, which is visible without removal, and because of the vibration of the hammer a continuing record 105 will be printed upon the dial without hindering the movement of the dial, so long as any one of the buttons is pushed. As a consequence a watchman can gain no advantage by plugging in any particular station, because 110 that would immediately result in a permanent and continuing record upon the dial. During the night, the brush 20 registering with slot 19, magnet 47 cannot be energized and lock-pin 49 cannot be withdrawn from eye 51. 115

We claim as our invention—

In a watchman's clock, the combination, with the time-train, of a plurality of electrically-operated recording mechanisms, an electromagnet in circuit with some of the operators of said recording mechanisms, a switch-carrying armature therefor, the said switch, an electric alarm, an energizing-circuit therefor consisting in part of said armature, and the terminal with which it may contact, a re- 125 130

setting electromagnet adapted to cause the resetting of the switch-carrying armature, means operated by the train for closing the alarm-circuit at predetermined times, and 5 means controlled by the time-train for subsequently closing the circuit of the resetting-magnet, for the purpose set forth.

In witness whereof we have hereunto set

our hands and seals at Indianapolis, Indiana, this 14th day of March, A. D. 1903.
